GAS BURNING APPARATUS

William A. Bulger, Chicago, Ill., assignor to Petroleum Heat and Power Company, New York, N. Y., a corporation of Delaware

Application August 5, 1932, Serial No. 627,545

11 Claims. (Cl. 158—110)

This invention relates to gas burning apparatus adapted for heating furnaces generally, and has for one of its objects the provision of a gas burning apparatus of improved and novel construction.

More specifically the present invention provides a construction wherein deflector rings are provided for directing the damper-controlled secondary air over the burner ports.

Another object of my invention is the provision of a gas burning apparatus in which refractory radiants are employed for absorbing heat from the gas flame and transforming it into radiant heat energy, these radiants being provided on their exterior with grooves disposed diagonally and roughly providing a helical formation, the effect of which is to impart a swirling motion to the combustion gases thereby retarding the speed of movement of these gases through the boiler and causing a wiping contact of the combustion gases with the inside walls of the boiler, to promote the efficiency of the burner.

A still further object of my invention is the provision of a gas burning apparatus adapted to be installed through the ashpit of a furnace, a seal being provided around the outside of the burner head between it and the wall of the furnace so that the ashpit section of the furnace or boiler is very effectively sealed at the grate line, thereby preventing heat losses through this part of the boiler and eliminating seepage of stray excess air currents at this point.

In the drawings accompanying this application:

Fig. 1 is a part sectional side elevational view of my improved apparatus as installed in a furnace;

Fig. 2 is a view similar to Fig. 1 but with additional parts broken away to show structural details;

Fig. 3 is an end elevational view of the rear end of the apparatus;

Fig. 4 is a section on the line 4—4 of Fig. 2;

Fig. 5 is a section taken substantially on the line 5—5 of Fig. 2; and

Fig. 6 is a sectional plan view.

Referring to the drawings in detail, F designates a furnace which, for example, may be of the ordinary house heating type. My improved apparatus which is shown installed in this furnace comprises inspirator tubes 1, each provided with a head 2. These heads are arcuate in plan and the top thereof provided with gas ports 3. This construction provides, therefore, a circular burner. The heads 2 are provided with lugs 4 and 5, the former supporting a radiant-supporting plate

6, and the latter an air deflector ring 7, the ring 7 completely surrounding or encircling the burner. The periphery of the radiant-supporting plate 6 is formed to provide an air deflecting ring 8. From an inspection of Fig. 5, for example, it will be apparent that the rings 7 and 8 are both spaced from the outer walls of the heads 2 to provide passages 9 for the travel of secondary air as will be brought out hereinafter.

Each of the inspirator tubes 1 is provided with 10 an integral leg 10 adapted to be bolted to the floor for instance and to support the whole structure so far described.

The burner head and its associated deflector rings, etc. are positioned in the furnace at about 15 the grate line, the tubes 1 extending from the ashpit to the furnace exterior. To prevent seepage of stray air currents past the exterior of the burner head I provide a seal shown at 11, in the form of cement or refractory, and supported on 20 the air deflector ring 7. The furnace wall has been designated 12.

The inspirator tubes 1 extend along the interior of a secondary air-conducting casing 13 which rests on the floor and extends through the ashpit opening for a short distance into the ashpit 14 itself. The outer end of the casing 13 is closed by a plate 15, equipped on its inner face with suitable means 16 for receiving the outer ends of the inspirator tubes 1 and with adjustable gas valves 17, 30 inlets 18 for primary air, and regulators 19 for the regulation or adjustment of the primary air. The gas inlet pipe is shown at 20.

This construction provides for the proper regulation of the primary air and gas.

21 designates an electrically operated gas valve which is of usual well known construction and as usual controlled from a room thermostat. The gas valve 21 as will be understood automatically opens and closes in accordance with the demands 40 of the room thermostat. As this structure is well known and constitutes no part of the present invention it will not be described in any more detail.

22 designates a damper operating lever adapted to be rocked by operation of the gas valve 21, and attached through spring and chain 23 and 24 to a damper 25 in the end plate 15 of the casing 13, so that as the gas valve is opened the damper 25 will fall open to admit secondary air to the casing, and as the gas valve closes the damper will be pulled 50 closed. The extent of opening of the damper 25 is adjustable by a screw 26.

The pilot shown at 27 underlies the deflector ring 8 so as to be protected from the heat of the burner.

The plate 6 is provided in its upper face with a concentric groove 28 for receiving upwardly extending and outwardly flaring refractory radiants 29. These radiants are made in sections provided 5 exteriorly with grooves 30 extending in a general diagonal direction with respect to the horizontal and as a whole providing helically disposed grooves for causing the products of combustion to swirl in their passage upwardly through the combustion 10 chamber of the furnace thereby retarding upward movement of these gases, and increasing the contact of the combustion gases with the wall 12 of the furnace.

What I claim is:

1. Gas burning apparatus comprising in combination a horizontally disposed burner head and vertically extending outwardly flaring radiants carried on the upper face of said head, said radiants being provided exteriorly with diagonally extending directing grooves for the hot gases rising from the burner head.

2. Gas burning apparatus comprising in combination a horizontally disposed burner head, vertically extending outwardly flaring radiants 25 carried by the said head, said radiants being provided exteriorly with grooves extending helically for directing the hot gases rising from the burner head.

3. Gas burning apparatus comprising in combination inspiriting tubes, a head for each tube, the upper wall of each head being provided with gas ports, air deflectors adjacent the said ported heads and concentric therewith, said air deflectors being supported by said heads, vertically extending outwardly flaring radiants carried by each of said heads, said heads each being provided exteriorly with grooves extending helically for directing the hot gases rising from the burner heads.

4. Gas burning apparatus comprising in combination inspiriting tubes, an arcuate head for each tube, the top wall of each head being ported, lugs on the said heads, and an air deflector ring at each side of the ported wall of said heads, said rings being supported by said lugs.

5. Gas burning apparatus comprising in combination inspiriting tubes, an arcuate head for each tube, the top wall of each head being ported, lugs on the said heads, and an air deflector ring 50 at each side of the ported wall of said heads, said rings being concentric with said heads and supported by said lugs.

6. Gas burning apparatus comprising in combination inspiriting tubes, an arcuate head for each tube, the top wall of each of said heads being ported, lugs on said heads extending inwardly and outwardly therefrom, a radiant-supporting plate mounted on said inwardly extending lugs and encircled by said heads, said plate being provided at its periphery with an air deflecting formation to direct secondary air outwardly toward said ports, and an air deflecting ring encircling said heads and spaced therefrom to provide a secondary air passage for directing air inwardly toward said ports, said last mentioned ring being supported by said outwardly extending lugs.

7. Gas burning apparatus comprising in combination inspiriting tubes, a head on the inner end of each tube, the upper wall of each head

being ported, supports for said tubes adjacent the inner ends thereof, lugs on said heads, an air deflector ring at each side of said heads, said rings being mounted on said lugs and supported thereby and cooperating with said ports, and radiants also carried by said heads and cooperating with said ports.

8. In gas burning apparatus for furnaces having a combustion chamber and a chamber below the combustion chamber, the combination of a 10 gas burner comprising a tube extending through said second chamber to said burner head for supplying a mixture of gas and air to the burner head, means for supplying secondary air to the burner head through said lower chamber about 15 the exterior of said tube, vertically extending outwardly flaring radiants carried by the upper face of said burner head, said radiants being provided exteriorly with diagonally extending directing grooves for the hot gases passing between the 20 radiants and the adjacent wall of the combustion chamber, and means for preventing the passage of secondary air between said radiants and the adjacent wall of the combustion chamber.

9. In a gas burning apparatus for furnaces 25 having a combustion chamber and a chamber below said combustion chamber provided with a side opening, the combination of gas burning apparatus comprising a burner head, a tube extending through said lower chamber to said burner 30 head for supplying a mixture of gas and air to said burner head, said tube extending through said side opening and upwardly into said combustion chamber, vertically extending outwardly flaring radiants carried by said burner head, 35 said radiants being provided exteriorly with grooves extending helically for directing hot gases rising from the burner head between said radiants and the adjacent wall of the combustion chamber, and sealing means for sealing the burner into 40 the furnace against the passage of air from said lower chamber between the radiants and the adjacent wall of the combustion chamber.

10. A burner for installation in a heater having 45 a combustion chamber wall, said burner having a head provided with means adjacent to said wall for discharging jets of fuel, a baffle of ceramic material comprising a plurality of sections arranged side by side and extending over said fuel jets and toward said combustion chamber 50 wall, and spirally extending ribs on said baffle for deflecting fuel jets and products of combustion into a spiral path in the space between said baffle and said wall.

11. A burner for installation in a heater having 55 a combustion chamber wall, said burner having a head provided with means adjacent to said wall for discharging jets of fuel, a baffle of ceramic material comprising a plurality of sections arranged side by side and extending over said 60 fuel jets and toward said combustion chamber wall, said baffle being formed in a plurality of sections, and a plurality of spirally extending ribs formed on said baffle sections for producing a whirling movement of gases in the space between 65 said baffle and said wall, some of the ribs of one section being arranged to form continuations of ribs of adjacent sections.

WILLIAM A. BULGER.
